(57) **CLAIM**

The ornamental design for a display screen or portion
thereof with animated graphical user interface, as shown and
described.

DESCRIPTION

FIG. 1 is a front view of a first image in a sequence of a
display screen or portion thereof with animated graphical
user interface, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The appearance of the animated graphical user interface
sequentially transitions between the images shown in FIGS.
1-7. The process or period in which an image transitions
to another image forms no part of the claimed design.

The broken lines show an exemplary article onto which the
display screen is positioned, and form no part of the claimed
design.
